CLAIM

The ornamental design for a public pay telephone set, as shown and described.

DESCRIPTION

FIG. 1 is a front and right perspective view of the upright stand, and the operative inner surface of the handset, of a public pay telephone set showing our new design spaced apart for facility of illustration;

FIG. 2 is a front elevational view thereof in cradled relationship;

FIG. 3 is a right side elevational view of the telephone set as shown in FIG. 2;

FIG. 4 is a top plan view thereof of the telephone set as shown in FIG. 2;

FIG. 5 is a left side elevational view thereof;

FIG. 6 is a rear elevational view of the telephone set as shown in FIG. 2; and,

FIG. 7 is a bottom plan view thereof with the cord omitted for convenience of illustration.
